UNITED STATES PATENT OFFICE.

JOSE ALVAREZ ALEA, OF HABANA, CUBA.

ARTICLE OF MANUFACTURE.

Application filed March 31, 1923. Serial No. 629,024.

To all whom it may concern:

Be it known that I, JOSE ALVAREZ ALEA, citizen of the Republic of Cuba, residing at Habana, Republic of Cuba, have invented 5 a new and useful Improvement in Articles of Manufacture; and I do hereby declare the following to be a full, clear, and exact description of the same.

This invention relates to a new article of 10 manufacture, which consists in a new hat made of straw or rattan, which presents a detail or attachment that improves its aspect and enhances its value, making its lines or contours elegant and original.

15 The invention is described with reference to the figures shown on the accompanying drawings in which the same reference numbers designate the same parts.

In the drawing:

20 Fig. 1 is a side elevation of the article or hat which is the object of the present invention.

Fig. 2 is a top plan view of the same.

Fig. 3 is a perspective view of the hat.

25 Fig. 4 is a partial diametrical vertical section in detail on an enlarged scale, as per line 4—4 of Fig. 2.

Fig. 5 is a top plan view in detail of one 30 of the straw strips which form the flange of the hat.

The hat 1 as shown in the drawing is made of straw or rattan and can be of any desired form since the novel feature which it presents is a double flange connected 35 with and projecting from the edge of its brim, around the entire circumference of the same. The flange comprises two strips 3 and 4 of the same material as the rest of the hat, each strip as seen from Figure 5, having

40 on one of its edges a projecting curled portion 3' or 4'. The strips have smooth border portions 3", 4" and are placed back to back with the curled portions facing outwardly and the parts 3" and 4" introduced between 45 and sewn to the members 5 and 6 forming the hat brim, so as to form a portion of the brim.

45 After the hat has been made as described above it is gummed and ironed and the brim and flanges formed as above described is 50 submitted to the process forming the subject matter of a copending application whereby the brim of the hat remains flat while the flanges which have been flattened out by the 55 ironing, again recover their original shape and project at right angles to the edge of the brim. The above is merely illustrative of one form of the invention and should not be considered in the limiting sense.

55 I now claim:

A new article of manufacture, comprising, 60 a hat made of straw, a brim on the hat, a flange provided on the outer edge of the brim and projecting on both sides of the 65 brim, the flange being formed by two strips made of straw, curled portions positioned 70 on the strips at spaced intervals, the strips being superposed with their curled portions facing outwards, and sewn to the outer edge portion of the brim.

In testimony whereof, I have signed my name to this specification in the presence of two subscribing witnesses.

JOSÉ ALVAREZ ALEA.

Witnesses:
